(74) Attorney, Agent, or Firm — Wayne & Ken, LLC;
Tony Hom(57) **CLAIM**

A new, original, ornamental design for a filter, as shown and described.

DESCRIPTION

FIG. 1 is a front view of a filter showing my new design;
 FIG. 2 is a back view thereof;
 FIG. 3 is a right view thereof;
 FIG. 4 is a left view thereof;
 FIG. 5 is a top view thereof;
 FIG. 6 is a bottom view thereof;
 FIG. 7 is a perspective view thereof; and,
 FIG. 8 is a sectional view of 8-8 in FIG. 1.
 The evenly spaced broken lines depict portions of the filter that form no part of the claim.

1 Claim, 8 Drawing Sheets(56)
